Des. 224,305
Patented July 18, 1972

224,305

PLURAL FLUID CONTROL MIXING AND SPRAY GUN

Wallace F. Krueger, 4401 Merriweather Road,
Toledo, Ohio 43623

Filed June 8, 1970, Ser. No. 23,367

Term of patent 14 years

Int. Cl. D23—01

U.S. Cl. D23—17

FIG 1

FIG. 1 is a side elevation view of the plural fluid control mixing and spray gun, showing my new design.

FIG. 2 is a perspective view taken from the top, bottom and right side thereof.

FIG. 3 is a perspective view taken from the front, bottom and left side thereof.

I claim:

The ornamental design for a plural fluid control mixing and spray gun, substantially as shown.
